UNITED STATES PATENT OFFICE.

ARTHUR J. MILLER, OF LELAND, ILLINOIS.

ELECTRICALLY-OPERATED ENTRANCE.

Application filed February 27, 1923. Serial No. 621,633.

To all whom it may concern:

Be it known that I, ARTHUR J. MILLER, a citizen of the United States, residing at Leland, in the county of La Salle and State 5 of Illinois, have invented certain new and useful Improvements in Electrically-Operated Entrances, of which the following is a specification.

My invention relates to means for automatically opening and closing a gate, door, or the like.

An important object of the invention is to provide apparatus of the above mentioned character, so constructed that when a vehicle, such as an automobile, is driven upon a platform, the gate or door will automatically move to the open position and remain held in this position, until the vehicle passes upon another platform arranged upon the 20 opposite side of the gate or door, at which time the gate or door will be automatically closed.

Other objects and advantages of the invention will be apparent during the course 25 of the following description.

In the accompanying drawings forming a part of this specification, and in which like numerals are employed to designate like parts throughout the same,

30 Figure 1 is a plan view of apparatus embodying my invention.

Figure 2 is a plan view of the box of the platform, showing the operating means therein,

35 Figure 3 is a transverse section taken on line 3—3 of Figure 2,

Figure 4 is a side elevation of the gate,

Figure 5 is a central vertical longitudinal section through the gear casings, parts 40 broken away,

Figure 6 is a horizontal section taken on line 6—6 of Figure 5,

Figure 7 is a perspective view of a segment and contact associated therewith,

45 Figure 8 is a diagrammatic view of the apparatus and circuits included therein, showing one circuit energized to open the gate with the lower platform depressed, the traffic being in the direction of the arrow,

50 Figure 9 is a similar view showing the upper platform depressed and the circuit closed to lower the gate, the traffic being in the direction of the arrow,

Figure 10 is a similar view showing the 55 upper platform depressed and the circuit

closed to open the gate with the traffic in the direction of the arrow, and,

Figure 11 is a similar view showing the lower platform depressed and the circuit closed to close the gate with the traffic in 60 the direction of the arrow.

In the drawings, wherein for the purpose of illustration is shown a preferred embodiment of my invention, the numeral 15 designates a pair of posts or uprights, carrying 65 the movable gates or door 16. These gates preferably embody longitudinal beams 17, connected by transverse strips or elements 18, pivoted thereto at 19. The longitudinal beams 17 are pivotally connected with the 70 posts 15, as shown at 20, to swing in a vertical plane. It is thus seen that the gates 16 swing vertically transversely of the road bed.

As more clearly shown in Figure 5, the 75 lowermost beams 17 are rigidly connected with gears 21, which are pivotally supported by the shafts or pivots 20. These gears are engaged by a toothed segment 23, pivotally supported at 24. The gears 21 and 80 toothed segments 23 are suitably mounted within casings or box 25, as shown. Each toothed segment or gear 23 has its lower end depending downwardly below the pivot 24 and is pivotally connected with a rod or pitman 25, extending outwardly for pivotal connection with the crank 26 of a shaft 27, suitably journaled in the box 25. The shaft 27 has a gear 28 rigidly secured thereto and this gear is driven by a similar gear 29 90 rigidly mounted upon a shaft 30. The shaft 30 is suitably journaled in the box 25. The shaft 30 is driven by a gear 31, rigidly secured thereto, and this gear engages a gear 32 rigidly mounted upon a shaft 33. The 95 shaft 33 has a larger worm gear 34 rigidly mounted thereon, which is driven by a worm gear 35, carried by a transverse shaft 38.

As clearly shown in Figure 4, the transverse shafts 38 are connected with the outer 100 ends of the armature shafts of motors 39 and 39', and the inner ends of these armature shafts are rigidly connected by a shaft 40, whereby the motors are mechanically connected. The armatures of the motors 105 will rotate together, and one motor will be receiving current while the other will not, as will be explained. The motors 39 and 39' and shaft 40 and associated elements may be arranged within a space 41, between 110

the posts 15, which space may be covered by a plate 42 or the like.

In Figure 1, A and B designate platforms, upon which an automobile or like vehicle is to be driven. These platforms are arranged upon opposite sides of the gate and at suitable distances therefrom. Each platform is arranged over a box or casing 43, suitably sunk into the road bed so that the platform is substantially flush with the upper surface of the road bed. As more clearly shown in Figure 3, diverging levers 44 have their outer ends pivoted at corners in the box 43, as shown at 45, to swing in vertical planes. The diverging ends of these levers are pivotally connected with each other and with a depending link 46 by means of a bolt 47. The link 46 has pivotal connection with a vertically swinging lever 48, pivoted at 49. The lever 48 carries near its free end a weight 50, which may be longitudinally adjusted thereon, as found advantageous. The numeral 51 designates a pair of diverging levers, pivoted at their outer ends within the box 43, near the upper ends of the corners thereof, as shown at 52. The levers 51 have their inner ends resting upon the levers 44. Each platform is provided with depending supports or lugs 53, which rest upon the levers 44 and 51, whereby these levers support the platform. When there is no load upon the platform, as indicated in Figure 3, the lever 48 is held depressed, and the platform is elevated.

The numerals 54 and 54' designate a switch element, pivoted upon an insulating support 55, and adapted to engage and disengage a coacting switch element 56 and 56'. Each switch element 54 and 54' is pivotally connected with a link 57, insulated therefrom. This link is pivoted to the free end of the lever 48. It is thus seen that when the platform is depressed, the switch element 54 will rise and engage the switch element 56.

The numerals 58 and 58' designate curved or segmented contacts which are rigidly mounted upon the segmental gears 23, and insulated therefrom. Each contact is provided at one end with an insulating portion 59. The contacts 58 and 58' are adapted to be engaged by a contact 60 and 60', carried by a support 61' and insulated therefrom.

Attention being called now to Figures 8 to 11, it will be seen that a wire 61 has electrical connection with the contact 58, and this wire extends across and has connection with a wire 62, which is electrically connected with the contact segment 58'. The wire 61 is connected at 63, with a wire 64, which is electrically connected with the switch element 54. The switch element 56 is connected with a wire 65, connected

with one pole of the source of current 66, the opposite pole of which is connected with a wire 67, which is electrically connected with the motor 39. The opposite pole of the motor is connected with a wire 68, which is connected at 69 with a wire 70. This wire 70 is connected with the contact element 60. The wire 70 extends across and is connected at 71 with a wire 72, which is connected with the contact element 60'. The wire 70 is also connected at 71 with a wire 73, electrically connected with the contact 56', and this wire is connected with one pole of the motor 39'. A wire 75 is connected with the opposite pole of the motor and is connected with one pole of a source of current 76. The opposite pole of this source of current is connected with a wire 77, which is connected with one end of the wire 61, as shown at 78.

Figure 8 shows the vehicle traveling in the direction of the arrow, from right to left, and as depressing the platform A. This closes the switch element 54. Current will now pass from one pole of the source of current 66, through wires 65, switch element 54, wire 64, contact segment 58, contact element 60, wire 70, wire 68, through motor 39, and wire 67, back to the opposite pole of the source of current 66. The motor 39 will now operate and the gates 16 will be elevated. When the gate is sufficiently elevated the vehicle is driven from the platform A and passes through the gate and the switch element 54 will then disengage the switch element 56. The gate will be held in the open position, by virtue of the worm wheel 35 engaging the worm wheel 34. When the vehicle passes upon the platform B, traveling in the direction of the arrow, Figure 9, a circuit will be closed and the motor 39' will operate to close the gates. The switch element 54' now engages the switch element 56', and the motor 39', will be energized and close the gate. When the gate is open, the contact segment 58 disengages the contact 60 while contact segment 58' engages its contact 60', as clearly shown in Figure 9. In the closed circuit for driving the motor 39', current passes from one pole of the source of current 76, through wire 77, wire 62, contact segment 58', contact 60', wire 72, wire 73, switch element 54', wire 74, motor 39', and wire 75 back to the opposite pole of the source of current 76. In Figure 10, the gate is regarded as closed and the automobile is driven upon the platform B, with the traffic in the direction of the arrow. This will bring the switch element 54' into engagement with the switch element 56', and a circuit will be closed for energizing the motor 39' and raising the gate.

In this closed circuit current flows from one pole of the source of current 76, through wire 77, wire 61, contact segment 58, contact 60, wire 62, contact segment 58', contact 60', wire 72, wire 73, switch element 54', wire 74, motor 39', and wire 75 back to the opposite pole of the source of current 76.

- 60, wire 70 to the point 71, wire 78, switch element 54', switch element 56', wire 74, through motor 39', and wire 75, back to the opposite pole of the source of current. The 5 gate is opened and when this is effected, the vehicle drives from the platform B and then passes through the gate upon the platform A. The switch element 54' will disengage the switch element 56', with the gate raised. 10 Contact segment 58 now disengages the contact 60 while contact segment 58' engages contact 60'. The motor 39 will now be energized to lower the gate, as switch element 54 engages switch element 56. In this closed 15 circuit current will flow from one pole of the source of current 66, through wire 65, switch element 56, switch element 54, wire 64, wire 61, point 78, contact segment 58', contact 60', wire 72, wire 70, wire 69, and wire 68, back 20 to the opposite pole of the motor 39 and then through wire 67 to the source of current 66.

Particular attention is called to the fact that each crank 26, upon making one half of 25 a revolution, will move the gate in opposite directions, up or down. It is therefore seen that each motor and associated elements is capable of opening and closing the gates, and as these motors are positively geared 30 together, they work in harmony, each motor opening or closing the gate, depending upon the direction of the traffic.

It will also be seen that when the gates are shifted to the completely opened or 35 closed positions, the contacts 60 or 60' will engage the insulating parts 59, thus opening the motor circuit and stop the movement of the gate or door elements, even though the vehicle remain on either platform. 40 It is to be understood that the form of my invention herewith shown and described is to be taken as a preferred example of the same, and that various changes in the shape, size, and arrangement of parts may be 45 sorted to without departing from the spirit of my invention or the scope of the subjoined claims.

Having thus described my invention, I claim:

50 1. The combination with a pair of gate

or door elements, a pair of cranks arranged near the gate or door elements, operative connections between the cranks and the elements whereby each element may be opened and closed upon a complete revolution of 55 its crank in one direction, a pair of motors for rotating the cranks for a complete revolution in one direction, a positive connection between the armature shafts of the two motors whereby either motor is capable of 60 rotating both cranks and hence serve to open and close both gate or door elements, circuits connected with the motors, platforms arranged upon the opposite sides of the door or gate elements, means operated 65 by one platform to close the circuit of one motor, and means operated by the other platform to close the circuit of the other motor.

2. The combination with a pair of gate 70 or door elements adapted to be shifted to opened and closed positions, a pair of cranks arranged near said elements, operative connections between the cranks and elements whereby the elements are opened and 75 closed upon a complete rotation of the cranks, gearing for rotating the cranks including worm gears, shafts having worms engaging the worm gears, a pair of motors having corresponding ends of their armature shafts connected with said shafts, a shaft arranged between the motors and connecting corresponding ends of the armature shafts whereby each motor may be driven to open and close both of said elements, circuits connected with the motors, platforms arranged upon the opposite sides of said elements, means operated by one platform to close the circuit of one motor for opening 80 the gate elements, means operated by the other platform to close the circuit for shifting said elements to the closed position, means for opening the circuit of one motor when the said elements are shifted to the open position, and means for opening the 85 circuit of the other motor when said elements are shifted to the closed position.

In testimony whereof I affix my signature.

ARTHUR J. MILLER.
